UNITED STATES PATENT OFFICE.

JAMES HALL TAYLOR, OF OAK PARK, ILLINOIS.

APPARATUS FOR MAKING NOZZLES.

Application filed March 15, 1924. Serial No. 699,510.

The present invention relates to a new and improved apparatus for making nozzles of the type commonly used in connection with steam boilers and oil-cracking stills. Owing to the high pressures and temperatures which are now in prevailing use in both of these fields, it has become necessary to construct these nozzles of a metal having a relatively higher tensile strength than heretofore used for this purpose. To forge nozzles from this metal and to prevent overstraining the neck portion of the nozzle, it is desirable that the stretching of this portion be limited. This I achieve by my improved apparatus.

Referring to the accompanying drawings illustrating my apparatus and the preferred sequence of steps in the process carried out thereby:—

Fig. 1 is a sectional view of the original blank;

Fig. 2 is a sectional view showing the first step of forming a flange on the blank;

Fig. 3 shows this flanged blank inserted in position between the dies which perform the following operations;

Fig. 4 shows the first action of the dies in drawing or shaping the flange formed on the lower edge of the blank downwardly in a curve;

Fig. 5 shows the step of forcing metal from the upper body portion of the blank down into the tubular neck of the nozzle;

Fig. 6 shows the nozzle in completed outline with a flange formed on the upper end thereof; and

Fig. 7 is a sectional view of the finished nozzle, with the end of the tubular neck punched out.

The wrought metal blank 10 is shown in Fig. 1. For high pressure nozzles, such as the present invention contemplates, the metal in the blank 10 is of high tensile strength.

The first step in the process is to form an annular flange 11 around the bottom of the blank by a suitable die operation, as shown in Fig. 2. This leaves the blank with an upper body of metal 10' and the lower flange 11.

The blank is now placed on the upper end of a tapered male die 15, which is in the form of a tapered stool. An outer annular female die 16 is then placed over the upper body portion 10' of the blank, being dropped

down onto the flange 11. This female die is split into two halves for convenient removal from over the nozzle, as I shall presently describe. The female die has a central die opening 17, the lower end of which joins 60 with the bottom surface of the die through a gradual curve 18. A spacer 21 is then mounted on the top of the female die 16 to prevent the initial part of the downward thrust of the die plate 22 from engaging the 65 upper projecting end of the portion 10'. The initial part of this downward motion is thus concentrated on the projecting flange 11, and operates to draw or shape this flange downwardly away from the body portion 70 10' to approximately the position and shape indicated in Fig. 4, where the flange conforms substantially to the curvature 18 of the female die 16. It will be apparent that the spacer 21 has the function of producing 75 concurrent motion between the die plate 22 and the female die 16 during a desired portion of the forming operation, but it will be obvious to those skilled in the art that other means may be employed to secure this concurrent motion during this portion of the forming operation.

After the flange has been shaped substantially as shown, the die plate 22 engages the body portion 10' of the blank, and thereafter 85 the pressure applied to the top of the blank forces the solid upper end of the blank down against the top of the male die 15 under the continued motion of the die plate 22 and the female die 16. The upper body 90 portion of the blank being confined laterally by the walls of the die opening 17, the heated metal is forced, under the very high pressure created between the die plate 22 and the top of the male die 15, down into the annular 95 opening between the male die 15 and the female die 16.

This downward forcing of the metal may be continued to the desired point depending upon the quantity of metal that it is desired to supply from the ball or body portion 10' to the tubular neck. Fig. 5 illustrates how far this operation of supplying or discharging metal from the body portion into the tubular neck can be carried. At 105 the completion of this operation the opposing die faces 18 and 23 will lie in substantial parallelism; or, if a tapered section is desired in the finished neck of the nozzle, these two die surfaces will lie at the proper 110

divergence for such a taper. The lower flange end 11 may be arranged to engage a bed plate 24, on which the stool die 15 rests, at the bottom of the stroke, so that this 5 flange will be flattened out horizontally in the plane of the finished flange. It will be noted that the upper solid end of the blank may flatten out somewhat, as illustrated in Fig. 5.

10 In performing the next step, the spacer 21 is removed and the ram or die face 22 is brought down against the bulged upper end of the blank, flattening this metal down into an annular recess 19 to form the upper 15 flange 25. While I have shown this annular recess as being formed in the top of the female die, it will be obvious that it may be formed in the bottom of the die plate. Such a recess is, however, only necessary when it 20 is desired to limit the size of the flange in this manner, as the flange could be formed between two flat faces on the female die and die plate. A thin disc of metal 26 is preferably left between the upper end of the male 25 die 15 and the bottom of the die face 22 to prevent contact between the dies.

As a final step, the disc 26 is removed. The female die 16 is a split die to permit of the removal of the nozzle.

30 I claim:

1. In die mechanism for forming nozzles, the combination of a male die, a female die, a die plate adapted to produce relative motion between said dies, and a spacer normally provided between said die plate and one of said dies, said spacer being removable to permit said die plate to impress its full pressure on the blank.

2. In die mechanism for forming nozzles, 40 the combination of a female die having a tapered die opening, a male die having tapered sides, said female die having a flange forming recess around the small end of said tapered die opening, a ram for applying pressure to said female die, and a removable

spacer adapted for interposition between said ram and said female die.

3. In combination, a male die, a female die, a die plate adapted to produce relative motion between said dies, said female die engaging a flange on the nozzle blank and shaping the same to form a portion of the tubular neck of the nozzle, and a spacer provided between said die plate and one of said dies, said spacer being proportioned in height to cause said die plate to contact with the end of said blank before the completion of the tubular neck.

4. In combination, a male die, a female die, a die plate adapted to produce relative motion between said dies, said female die engaging a flange on the nozzle blank and shaping the same to form the first portion of the tubular neck of the nozzle, and a spacer normally provided between said die plate and said female die, said spacer being proportioned in height to cause said die plate to engage with the end of said blank and apply pressure thereto after the formation of said first portion of the tubular neck 70 to force metal from the solid part of the blank into a continuation of said tubular neck, said spacer being removable to permit said die plate to impress its full pressure on the blank.

5. In die mechanism for forming nozzles, in combination, a female die having a flaring opening therethrough, a male die relative to which said female die moves, said male die being adapted to enter said opening in said female die, and a die plate movable as said female die relative to said male die, whereby a blank may have a flange portion thereon shaped into a tubular neck and metal from its body forced between said dies for addition to said neck.

In witness whereof, I hereunto subscribe my name this 10th day of March, 1924.

JAMES HALL TAYLOR.
